Inventor:

Friedrich Hoppe

United States Patent Office.

FRIEDRICH HOPPE, OF STUTTGART, GERMANY, ASSIGNOR TO THEODOR HAHN.

Letters Patent No. 102,820, dated May 10, 1870; antedated April 28, 1870.

IMPROVEMENT IN COMBINED LATCH AND LOCK.

The Schedule referred to in these Letters Patent and making part of the same.

To all whom it may concern:

Be it known that I, FRIEDRICH HOPPE, locksmith of the court in Stuttgart, in the Kingdom of Wurtemberg, Germany, have invented a new and useful Improvement in Locks; and I do hereby declare the following to be a clear and exact description of the nature thereof, sufficient to enable others skilled in the art to which my invention appertains to fully understand and use the same, reference being had to the accompanying drawings making part of this specification, in which the figure is a view of the interior of the lock.

My invention relates to that class of locks in which there are no springs, but in place thereof a weight or weights, which answer the same purpose; and

It consists in jointing a weight to the piece which raises one end of the latch, which is also adapted to act as the locking-bolt, whereby advantages are gained, as will be hereinafter more fully described.

In the drawings—

a represents the bolt and latch, which has a fulcrum on a pin or stud, *e*, and describes the arc of a circle in the direction 1.2.

b is the tumbler, which may be pivoted to said bolt and latch *a* and move with it.

c is the nut, through which passes the spindle of the knob, and to it is secured the raising-lever *h*, which is adapted to be pressed down against the rear end of the bolt, and thereby elevate its front end.

This raising-lever is jointed, as at *g*, to one end of

a weighted piece, *d*, whose free end is intended to bear against the upper side of the tumbler *b*, or a projection thereof.

It will be seen that when the device is employed as a latch, the lever *h* is caused to raise the latch *a*, whereby it can be withdrawn from the keeper.

In order to lock the bolt *a*, the key is properly introduced into the casing, and, on being manipulated, clears the tumbler of the pin *e* and advances the bolt.

The weight *d* constantly bears against the tumbler, and causes it to drop on the pin *e* at the proper time, and thereby returns the bolt in a locked position.

The joint between the weight *d* and lever *h* allows the former to be elevated by the forward motion of tumbler without moving the lever *h*, whereby the latter offers no resistance to said motion, which would not be the result if the lever and weight were rigidly secured together.

I dispense with springs, and produce a combined latch and bolt in a simple manner.

Having thus described my invention,

What I claim as new, and desire to secure by Letters Patent, is—

The weight *d*, jointed to the raising-lever *h*, in combination therewith and with the bolt *a* and tumbler *b*, operating together substantially as herein described.

FRIEDRICH HOPPE.
